UNITED STATES PATENT OFFICE.

GEORGE D. KINSEY, OF BROOKLYN, NEW YORK, ASSIGNOR TO THE AUSTRALIAN KNITTING COMPANY, OF PATERSON, NEW JERSEY.

DESIGN FOR KNITTED FABRIC.

SPECIFICATION forming part of Design No. 19,058, dated April 23, 1889.

Application filed March 7, 1889. Serial No. 302,337. Term of patent 7 years.

To all whom it may concern:

Be it known that I, GEORGE D. KINSEY, of Brooklyn, in the county of Kings and State of New York, have invented and produced a new and original Design for Knitted Fabrics, of which the following is a specification.

The accompanying drawing illustrates a design embodying my invention, the design being shown in the white portions of the figure.

A designates approximately parallel lines constituting the side edges of the design.

B designates an approximately diamond-shaped figure. Extending from the figure B are approximately straight parallel portions a. Below the said portions a, and approximately in line therewith, are other straight

portions, b, extending from another approximately diamond-shaped figure, C. Intermediate of the inner corners of the portions a b is a dot-like figure, c. At the sides of the portions a b, and intermediate of the figures B C, are approximately T-shaped portions D. Between the figure C and another figure, D, beyond it are two straight portions, d, extending widthwise of the design. 20 25

What I claim as my design is—

The design for knitted fabrics, substantially as herein shown and set forth.

GEORGE D. KINSEY.
